STAPLING MACHINE OR SIMILAR ARTICLE

John J. Power, Westbury, N.Y., assignor to Swingline
Inc., Long Island City, N.Y.

Filed May 7, 1970, Ser. No. 22,881

Term of patent 14 years

Int. Cl. D19—02

U.S. Cl. D8—50

FIG. 1

FIG. 2

FIG. 3

FIG. 5

FIG. 4

FIG. 1 is a side elevational view of a stapling machine or similar article showing my new design.

FIG. 2 is a top plan view thereof.

FIG. 3 is a bottom plan view thereof.

FIG. 4 is a front elevational view thereof.

FIG. 5 is a rear elevational view thereof.

The opposite side of the stapling machine not shown is similar to the side disclosed.

I claim:

The ornamental design for a stapling machine or similar article, as shown and described.
